WINDING MACHINE

Edward J. Abbott, Wilton, N. H., assignor to
 Abbott Machine Company, Wilton, N. H., a corporation of New Hampshire

Application January 5, 1931, Serial No. 506,530

3 Claims. (Cl. 242—43)

This invention relates to winding machines and relates more particularly to the traverse devices of such machines, and to various strand-handling machines performing a winding function.

5 My invention is particularly applicable to machines having traverse devices adapted to lay a winding strand (for instance, of yarn) in successive layers of reversed quick-pitch spiral windings, thus to form a headless self-sustaining 10 cylindrical or conical packages or cheese, and will be explained in this connection. The present application contains numerous features and attains certain of the objects of my copending application, Serial No. 476,776, filed August 21, 15 1930, now Patent No. 2,135,485 entitled "Machine and method for preparing yarn packages," and is in part a continuation of that application.

Among the objects of the present application 20 are to provide in a winding machine a more durable rotary traversing element than heretofore, and to provide a traversing device which may be run continually at high speed without excessive vibration or wear and without deviation 25 of the winding strand from the desired pattern of winding.

The present invention, while possessing features of general applicability in winding machines, is especially adapted for cooperation with 30 the circulatory carriers and general organization of cheese winding machines of my Patent No. 1,609,639 dated December 7, 1926, of the patent of E. J. and W. G. Abbott, No. 1,700,425, dated January 29, 1929, and of my above co-pending application. My invention has for another of its objects to provide in such machines a relative adjustment of the traversing devices and of the holders of the winding packages on 35 the carriers of circulatory textile machines, such that each package may be wound on its core in the same position with relation to the lengthwise dimension of the core. Accordingly a package wound on one of the carriers, and then depleted by unwinding, may be built up to full size on 40 any of the machine's other carriers, indiscriminately chosen. Thus a circulatory-carrier cheese winding machine, improved by my present invention, may be used for the building up of depleted packages without regard to which carrier is utilized for such supplemental winding, the operator (or an automatic substitute there-of as disclosed in Patent No. 1,700,425) preferably placing the depleted package on the winding spindle of the first inactive carrier which 45 passes. The improvement of the present invention

then renders it possible for the winding machine to complete a partially depleted or unfinished package by laying supplemental layers of windings in exact endwise correspondence with the original layers of reversed spiral windings 5 of the package, so that shall be no appreciable discrepancy between the new end surfaces defined by the cusps of the new spiral windings and the old end surfaces defined by the similar cusps of the original underlying spiral 10 windings.

Numerous other objects of invention, advantages, and features of novelty will be apparent from a consideration of the specific instance of my invention explained by way of example only, 15 in this specification and its accompanying drawings.

In the drawings:

Fig. 1 is a diagrammatic plan view of a circulatory-carrier winding machine to which the 20 present invention is particularly applicable, this view omitting many of the frame, driving and controlling parts of the machine, and all but two of its numerous circulating winding carriers, for clarity of illustration;

Fig. 2 is a fragmentary vertical section on the line 2—2 of Fig. 1, showing the upper portion of one of the circulatory winding carriers on the guideway of the machine;

Fig. 3 is a horizontal section on the line 3—3 30 of Fig. 2, showing in plan the traverse mechanism of the carrier, the cover plate of the carrier being removed to expose parts beneath;

Fig. 4 is a fragmentary vertical section on the line 4—4 of Fig. 3 through the rotary traverse 35 barrel of the carrier and its driving roll;

Fig. 5 is a plan of the strand traverse guide of Fig. 3, to a larger scale;

Fig. 6 is a side elevation of one of the circulatory carriers of the machine, the cover plate 40 of the carrier and the tension, stub-catching and detector devices mounted thereon and associated therewith being removed to show the rotary traverse barrel;

Figs. 7, 7^a and 7^b are fragmentary views, taken 45 on the line 7—7 of Fig. 4, at respectively different times in the period of rotation of the traverse barrel or cylinder; and

Fig. 8 is a fragmentary horizontal section on the line 8—8 of Fig. 6, showing one of the two 50 opposite end bearings of the rotary traverse barrel; and

Fig. 9 is a fragmentary horizontal section on the line 9—9 of Fig. 2.

Referring to Figs. 1 and 6, the machine illus- 55

trated as exemplifying the present invention includes in common with the machines of the above patents and application, a continuous guideway constituted of upper and lower rails 4 and 5 supported by any suitable frame, and defining a closed path of circulation for a large number of winding carriers 10 along opposite straight and semi-circular runs. Suitable means for moving the carriers along the guideway may 5 include an endless chain 30 running on sprockets 36, 36 (one of which is suitably driven), the carriers being severally connected to this chain as hereinafter described so as to be moved thereby in the direction of the arrow x in Figs. 1 and 10 15 6.

As preferably constructed an individual winding carrier includes an upright frame element or plate 60 (Fig. 6) adapted to bridge the distance between the rails 4 and 5 and provided at 20 its lower end with a horizontal projection 61 carrying an anti-friction roll 62 and a steady pin 63, roll 62 and pin 63 embracing between them the vertical flange of the rail 5.

At its upper end the plate 60 may be integral 25 with or attached to an upper head portion 65 which constitutes a part of the frame of the carrier 10, for example by bolts 64. The head 65 has outwardly projecting parallel end plates 66 and 67 spaced apart to provide room between them for 30 a rotary traverse cylinder 70 having a groove therein which determines the configuration of the wound layers in the winding package. One of the end plates of the head 65 may be extended as shown at 68 in Fig. 2, and terminate in a split 35 clamp 66^a adapted to retain a stationary pivot pin 66^b. Upon this pin, a package-carrying arm 71 may turn, this outer end of this arm 71 forming a split clamp for a spindle 72 for a winding core or package carrier w (Fig. 2). As shown in plan 40 in Fig. 9, the outer portion of the package-carrying arm 71 is provided with a boss 71^a surrounding the spindle 72, the boss being of appropriate size and shape to form an abutment for the rear end of a rotating core w as the core is rotated by 45 the roll 50. As the carrier progresses along the tractor roll, the reaction of the roll 50 upon the core or a winding package thereon, serves yieldingly to retain the rear end of the core w in 50 contact with this abutment, thus accurately positioning the core in an axial direction with respect to carrier; regardless of the exact length of the core.

A suitable molder for a supply of yarn to be 55 wound is provided on the carrier, preferably in the form of a spindle pin 122^a (Fig. 6) adapted to receive a spinning or like bobbin. The supply holder is located in position for a winding strand leading therefrom to pass the traverse barrel 10 on its ways to a winding package on the spindle 72, the traverse barrel 70 being provided for the purpose of imparting reciprocatory movement to the part of the strand approaching the winding package to cause the strand to lie on the package 65 in overlapped layers of quick-pitch spirals. This manner of winding forms the typical Fiji-wound headless self-sustaining package of cylindrical or conical form having the desirable property of extreme ease of unwinding.

70 For rotating the winding package so as to wind thereon, any suitable driving instrumentation may be employed, but preferably the machine is equipped with drive means common to a plurality of circulating winding packages. Such drive 75 means is herein illustrated as including the driven

tractor rolls 50 and 51 of the above patents and application, these driven tractor rolls extending along opposite straight portions of the guideway, and having associated therewith any suitable motor or connections to a source of power, such for example as is described in the above patents and application. With such a construction the length of the lever arm 71 is such as to bring the surface of winding core w or the winding thereon always into surface contact with one of the rolls 50 or 51 adjacent to which the carriage 10 is being traversed, and the offset position of the pin 66^b is such as to provide an arm 71 long enough to sweep a sufficient arc for the expected radius of the carrier w and the winding upon it. In normal operation the weight of the arm 71 and its attachments holds the winding mass firmly in frictional contact with the upper surface of the tractor roll 50 or 51.

On the back face of the head 65 at points 20 suitably laterally separated, studs 86 may be provided to carry anti-friction rolls 87 which rest on the top surface of the rail 4, and support the weight of the carriage.

Referring now to Figs. 6 and 8, the traverse cam 70, suitably grooved at 70^a, has in a recess at its end an outer ball race 88 taking over a series of balls 90^b supported by an exterior groove in a stationary inner race 81 provided with a nipple 92 fast thereto. Nipple 92 carries a cross pin 83 to take over the forked and reduced inner end of a pintle 94 which may be retained in a hole in the member 67 of the head 65, as by a set screw 94^a. Preferably both ends of the cylinder are provided with similar bearings, the pintle 94 at the opposite end of the cylinder being secured in an opening in the member 66 of the head 65. This arrangement is such that yarn or fly does not tend to work around the pintle 94, since the latter is 35 stationary.

An annular guard plate 90^c is preferably fitted 40 into the opening of the recess of the cylinder, substantially closing the recess about the pintle 94, to protect the anti-friction bearing. In order that the anti-friction bearing may be easily 45 lubricated, the pintle 94 is provided with a conduit 94^b for transmitting lubricant to the bearing. As shown, the pintle is hollow throughout its 50 length, the conduit 94^b extending to the outer end of the pintle and there being closed by a spring-pressed cap or button 94^c of a suitable fitting 94^d adapted to receive lubricant from a grease gun or the like.

The traverse cylinder preferably derives its 55 operative motion from a source common to that of the driving motion of the winding package; in the illustrated machine the traverse cylinder is frictionally driven by the tractor roll 50 or 51. Preferably the traverse cylinder is provided at 60 each end with a friction ring 70^b of cork, cork composition, felt, rubberized felt, rubber aggregated ground cork, or any other durable friction material, these rings projecting slightly beyond the cylindrical surface of the cam body.

A winding machine according to the present invention may have a large number of carriers 10, each comprising an individually constructed and assembled unit which includes a unit frame carrying one of the rotary traverse elements 70 and 75 the spindle 72 or analogous holder for the core of the winding package. In the use of the illustrated machine, cylindrical or conical headless self-sustaining strand packages are built up on the several carriers, the packages being wound to 75

a predetermined desired maximum diameter, and then removed from the machine.

In using these packages, it often happens that a package will be but partially exhausted, whereupon it is desired to wind on the partially exhausted package other windings sufficient to bring the package again to its maximum diameter.

It will be understood that the relation of the cam groove 70^a lengthwise with respect to the 10 spindle 72 or analogous holder for a core of a winding package determines the lengthwise placing of windings on a core or winding package. In the absence of means whereby a lengthwise adjustment could be obtained between the 15 grooved barrels 70 and the corresponding spindles, the slight differences in form between the various carrier units of a given machine would result in the practical impossibility of causing a subsequent winding formed on one 20 unit to correspond in lengthwise position on its core to an underlying winding previously formed on a different unit.

My invention therefore preferably provides an 25 adjustment of the relative positions of the holder for the winding package, and of the barrel 70 of each individual carrier unit of the machine. Preferably, as shown in Figs. 6 and 8, the two side plates 66 and 67 of the carrier unit are spaced sufficiently from the ends of the barrel 70 30 to permit the barrel 70 to be moved axially to some extent. Referring to Figs. 2, 6 and 8, the pintles 94 for the barrel are normally held fast by the screws 94^a. By loosening these screws on any given carrier, the two pintles and the barrel 35 70 of the carrier unit may be moved axially to such a point that the lengthwise positioning by the barrel 70 of wound layers on a winding package core is the same as that of the wound layers upon a core on any other unit of the machine, 40 or other similar machine. Referring to Fig. 9, the reference character *d* indicates the distance from the end of the core *w*, and the abutment 71^a against which it presses, the series of cusps of the strand windings *S* on the core. By loosening the screws 94^a and shifting the rotary 45 traverse barrel 70 and its pintles 94 axially, the range of traverse of the winding strand may be shifted to adjust this distance *d* to the desired amount. Preferably in a given machine, the 50 rotary traverse barrel of the several carrier units are individually adjusted so as to lay the windings on each of the several winding cores at the same distance from the rear end of the core. In this way the units of the machine may be rendered 55 interchangeable in respect to the completion of partially depleted packages on any of the several carrier units to produce outwardly substantially identical full packages. Thus a package wound on one unit of my machine, and then partially depleted by unwinding (as for example in a warper creel) may be placed on any of the spindles of the machine and brought to full size by winding additional layers of quick-pitch spiral windings thereon, the ends of these 60 additional layers collectively defining surfaces conforming to the end surfaces of the layers remaining from the previous winding operation.

Referring now to Fig. 2, the head portion 65, including end plates 66 and 67, of the carriage 70 is preferably arranged to have limited motion toward and away from the tractor rolls 50 and 51 for the purpose of providing freedom in respect to the rail 4 and the roll 50 or 51, for accommodating curvatures at the end of the machine, 75 and to enable the traverse cam 70 to be provided

with bearings without lateral freedom of motion, provision being made for resiliently urging the upper part of the carriage toward the tractor roll, thereby holding the rotary traverse cam in frictional driving contact with the tractor roll. 5 As best shown in Figs. 2 and 3, the head 65, preferably an integral casting, is provided not only with the outstanding end members 66 and 67, but is also provided with rearwardly projecting lugs 76 above the plane of the rail 4, said 10 lugs being vertically bored. The bore in one lug 76 receives the central portion of a pin 77 whose opposite end portions are disposed in bores in the forked end of a link 79 having a bearing hole at its other end to receive a pivot pin 80 carried 15 by the chain 30. The bore in the other lug 76 receives a pin 81 on which is pivoted a link 82 carrying a vertical axle pin 83 for an anti-friction roll 84. Link 82 is provided with a lug into which is hooked a tractor rod 85 extending 20 through a bore 86 in the head 65 and provided with a spring 87 adjustable by a nut 87^a. The spring 87 urges the roll 84 toward the head 65 and against the interior or rear vertical face of 25 the rail 4.

Inward or rearward motion of the head 65, thus induced, is limited on curved portions of the guideway by anti-friction rolls 88, 89 on vertical downwardly projecting studs disposed respectively near opposite ends of head 65 and adapted 30 to bear against the outer face of the rail 4. It will be observed that the contact points of the rolls 88 are laterally separated from the bearing point of the roll 84; this permits a controlled positioning of the upper end of the carriage 10 in 35 respect to the curved parts of the rail and normally provides freedom between the rolls 88 and the roll 50 or 51 sufficient to permit the spring 87 to hold the traverse cam 70 in pressure contact with the tractor roll 50 or 51. 40

The fact that the pressure roll 84 has its point of contact with the rail 4 half-way between the points of contact of the tires 70^b and the tractor roll 50 or 51, permits an equalization of the pressure on these two tires, and makes for longer 45 wear.

While various constructions of traverse devices operating on the principle of a rotary grooved cylinder may be employed in the circulating carriers of the machine, I prefer to 50 employ a grooved cam cylinder of small diameter relative to the maximum attainable diameter of the wound package and to provide in the cylinder a spiral groove having no more than maximum operative pitch but crossing itself at 55 least once, and usually several times. Such a cam preferably comprises, as shown, an essentially solid bar of steel. The cam, by virtue of its construction, may readily be case-hardened in the region of its groove by heat treatment, 60 and is preferably thus made. The feature of the cam groove crossing itself (preferably several times as shown) is an aid to enabling the cam to be case-hardened without distortion, since with the cam groove thus formed the body 65 of the cam is much more nearly symmetrical than if the groove traversed the cam without crossing itself. The solidity of the cam and its moderate diameter (as contrasted particularly to hollow large diameter cams generally used in 70 strand traversing mechanism) are material aids in enabling the cam to be case-hardened without distortion, a solid body of moderate diameter being obviously less subject to distortion under heat treatment than a large hollow body. The case- 75

hardened cam of the present machine offers great resistance to wear and is of improved durability.

The preferred illustrated embodiment of the invention utilizes in conjunction with the groove 5 of the rotary traverse cylinder an improved traversing slider engaging the winding strand and reciprocated back and forth by means of a follower element engaging the said groove.

Referring to Figs. 3, 4 and 5, the head of the 10 carrier is provided with a polished round steel rod 100^a fastened to the opposite plates 66 and 67 by nuts 100^b and constituting one guide for a slider 101^a having revolvably mounted in its lower end a pin 104^a (Fig. 4) which carries a 15 cam follower 105^a engaging the cam groove of the traverse cam 70.

Referring to Figs. 2 and 4, it will be observed that the axis of the guide rod 100^a is in a vertical plane intermediate the vertical planes of the 20 axes of the roll 50 and the traverse cam 70. The shape of the slider as viewed from the side in Fig. 4 may be characterized as generally triangular, the slider fitting within the approximately triangular space defined by the roll 50, 25 the traverse cam 70 and a cover plate 110 for the cam. The slider, as shown in Fig. 4 is provided with a part 101^b extending laterally from the guide rod toward the point of contact of the winding mass and tractor roll 50, this part 30 carrying an upturned extension 106 comprising the slotted yarn-engaging traverse eye of the slider, and is also provided with a part 101^c extending laterally from the guide rod opposite to part 101^b. These laterally extending parts 35 101^b and 101^c are preferably flat on their upper surfaces, as shown in Fig. 5 to permit these parts to slide in engagement with the under surface of the cover plate 110 as shown in Fig. 4. The cover plate thus constitutes a key to prevent the slider 40 from rotating on its guide rod 100^a and also a guide relatively close to the bite of the tractor roll 50 and winding package to prevent vibration of the slider as the latter is traversed to and fro by the cam 70. The cover plate 110 acts as a 45 yarn guide and is preferably bent at 110^a in a projecting angle in the path of the yarn, so that the yarn runs in contact with the cover plate from this point 110^a until it leaves the cover plate at the traverse eye 106. The arrangement of 50 parts whereby the slider 101^a is kept in constant sliding contact with the cover plate 110 close to the traverse eye, insures that yarn passing over this portion of the plate will be picked up and traversed by the slotted traverse eye at high 55 speeds of the eye which would cause undue vibration were the slider not thus guided. The attained diminution of vibration of the traversing slider permits the upturned part 106 comprising the traverse eye to be relatively short, and the 60 slot in this eye relatively shallow, thus facilitating picking up of the yarn strand by the fast-moving slider.

It will be readily apparent that elimination of undue vibration of the traverse eye 106 apart from its intended reciprocatory motion across the winding package is very desirable for the purposes of diminishing wear of the moving parts and preventing unintended disengagement of the strand and preventing deviation of the 70 winding strand from its intended pattern on the winding package. To these ends the illustrated cam follower element is especially formed to operate with the groove 70^a of the barrel 70 for smooth running under conditions of extremely 75 high speed.

The traversing groove 70^a may be considered to be constituted of a right-hand spiral portion 70^{a'} and a left-hand spiral portion 70^{a''}, (Figs. 7, 7^a and 7^b) these two portions being joined at their ends by curved connecting portions 70^{a'''}. 5 The rotation of the cylinder is in the direction of the arrows *v* in Figs. 7, 7^a and 7^b. Referring to Fig. 7^b, the cam follower element 105^a is shown as engaged by the right-hand spiral portion 70^{a'} of the groove. The cam follower element 105^a is 10 shaped on its right-hand side surface so that at least two longitudinally spaced points on this side surface will simultaneously contact with the driving side wall of this portion 70^{a'} of the groove, and preferably for the major portion of such 15 surface substantially to conform to this driving side wall of the groove. Thus the follower element as it is pressed by the driving wall of the groove is steadied thereby against oscillation about the axis of its pin 104^a.

The opposite or left side surface of the cam follower element is likewise similarly shaped so that at least two longitudinally spaced points will contact with the driving wall of the left-hand spiral portion 70^{a''} of the groove, and preferably 25 for the major portion of said surface of the follower substantially to conform to this driving side wall of the groove.

The capability of the follower in its preferred 30 illustrated form to conform successively to the driving walls of the oppositely inclined spiral portions of the groove involves a certain freedom of motion in these portions of the groove as clearly shown in Fig. 7^b wherein the right-hand side of the follower is shown as conforming to the 35 driving wall of the right-hand spiral portion 70^{a'} of the groove.

Preferably the lengthwise extent of conformity of the side surface of the follower to the driving wall of the groove is greater than the length of a 40 gap left in the driving wall at the places of crossing of the right and left hand portions of the groove, and in the illustrated preferred embodiment is approximately twice the length of such gap. Thus referring to Figs. 7^b and 7^a, 45 the illustrated follower is shaped to conform to the driving wall of the groove over a distance included within the construction lines *a* and *b*, which are distant approximately twice the length of the gap in the wall of the groove. As a consequence it is assured that while the follower is 50 crossing the gap, the follower will be adequately held by a contact with the unbroken parts of the wall against oscillation about the axis of its pin 104^a and against attendant slapping or 55 abrupt striking against one or the other walls of the groove. Referring to Fig. 7^a it will be apparent that before the cylinder has advanced to bring the gap in the wall opposite to the pivot pin 104^a about which the follower would tend to rotate, the forward end of the follower will 60 have engaged the unbroken part of the groove wall past the gap.

While I have described the preferred form of follower as conforming to a wall of the cam 65 groove, approximate as well as absolute conformity will usually suffice to give an easy-running long-lived follower evincing freedom from vibration. Thus while the side driving wall of the groove may constitute a warped surface generated by a radial line rotating and advancing axially of the cylinder, the pitch of the groove is not in general steeper than will admit of a straight-sided follower element approximately 70 conforming to the driving wall of the groove. 75

Thus with the illustrated cam cylinder having a diameter of about $1\frac{1}{8}$ inches and a radially cut groove of rectangular cross-section with an axial traverse of 6 inches in three revolutions, the follower illustrated herewith in conjunction with this cam may be characterized as having straight sides between the construction lines *a* and *b*.

The forward and rear, or leading and trailing, ends 105^b and 105^c of the follower are preferably tapered or rounded to facilitate the transfer of the follower from one spiral portion of the groove to the other at the curved connecting portions $70^a'''$ of the groove at opposite ends of the cam, the curvature of the ends of the follower preferably substantially coinciding with the curvature of the connecting portions $70^a'''$ of the groove, as shown in Fig. 7. Referring to Fig. 7, the follower will be seen at the end point at which it is transferred from the right hand spiral portion to the left-hand spiral portion of the groove, the tapered or rounded end portions of the follower engaging the outer roll of the curved connecting portion of the groove at this point, while the substantially straight intermediate portion of the follower engages the inner wall of this portion of the groove. Thus the follower preferably has little or no lost motion at this point and is not free to vibrate within the groove as it passes from one right or left hand portion of the groove to the other.

As contrasted with a follower of oval or like shape having a distinctly bowed or convex middle portion, the follower described herein affords a materially increased area of contact with the groove walls. As a consequence, the life of the follower is materially prolonged, wear is retarded, and vibration attendant upon wear is diminished.

It should be understood that the present disclosure is for the purpose of illustration only and that this invention includes all modifications and equivalents which fall within the scope of the appended claims.

I claim:

1. In a winding machine for yarn and the like, the combination of a traverse cam, a slider adapted to be moved to and fro by the cam, a traverse eye on the slider, and a cover plate for the cam, said cover plate having one surface positioned to guide the slider as the latter is moved, and having its opposite surface disposed to constitute a guide for yarn approaching said traverse eye.

2. A winding machine of the type having means for holding a winding mass of yarn in peripheral contact with a rotatable roll during winding, the machine including a cylindrical traverse cam disposed adjacent and generally parallel to the yarn-contacting roll, a slider movable to and fro by the cam, and a guide for the slider disposed in a plane intermediate the vertical planes of the axes of said roll and said cam, said slider including a part extending from said guide toward the point of contact of the winding mass and said roll and including an upturned part adapted to engage and traverse the yarn.

3. A winding machine of the type having means for holding a winding mass of yarn in peripheral contact with a rotatable roll during winding, the machine including a cylindrical traverse cam disposed adjacent and generally parallel to the yarn-contacting roll, a slider movable to and fro by the cam, a guide rod for the slider disposed in a plane intermediate the vertical planes of the axes of said roll and said cam, said slider including a part extending laterally from said guide rod toward the point of contact of the winding mass and said roll and a part extending generally in the opposite direction therefrom, and a cover plate for the cam positioned to contact with the two laterally extending parts of the slider as the latter is moved to and fro.

EDWARD J. ABBOTT.
